(57) **CLAIM**

The ornamental design for pocket umbrella and container, as shown and described.

DESCRIPTION

FIG. 1 is front perspective view of a pocket umbrella and container showing our new design;

FIG. 2 is a front view of the pocket umbrella and container with the umbrella partially extended thereof;

FIG. 3 is a front view of the pocket umbrella and container with the umbrella fully extended thereof;

FIG. 4 is a top right side perspective view of the pocket umbrella and container of FIG. 3 with extended umbrella; the left side being a mirror image thereof;

FIG. 5 is an enlarged top right side perspective view of the pocket umbrella and container of FIG. 4

FIG. 6 is a bottom perspective view thereof; and,

FIG. 7 is a top perspective view thereof.

The broken lines shown in the drawings are included for the purpose of illustrating portions of the article that form no part of the claimed design.
